UNITED STATES PATENT OFFICE.

GEORGE H. F. SCHRADER, OF NEW YORK, N. Y.

DESIGN FOR A TIRE-VALVE CAP.

SPECIFICATION forming part of Design No. 25,774, dated July 14, 1896.

Application filed May 26, 1896. Serial No. 593,186. Term of patent 14 years.

To all whom it may concern:

Be it known that I, GEORGE H. F. SCHRADER, a citizen of the United States, residing in New York, in the county and State of New York, have invented and produced a certain new and original Design for Tire-Valve Caps, of which the following is a specification.

The new design relates to the shape of tire-valve caps.

10 The new design is shown in the accompanying drawings, in which—

Figure 1 is a side elevation of the cap; and Fig. 2 is a perspective view thereof, showing the top and side of the cap.

15 The distinctive features of the new design are, as shown in the drawings, a smooth cylindrical band A, an abrupt shoulder B below this band, a wide serrated annular band C above the band A and of greater radial projection than the latter, an annular smooth top part D, shown as slightly convex, bulging, and tapering, and a smooth cylindrical protuber-

25 ance E at the center thereof. The part E is concentric with the other parts of the cap and of much smaller diameter.

The band C has a peculiar roughened appearance and is of greater diameter than the adjacent parts. It is distinctive in appearance. The wide smooth cylindrical part A beneath this band is in striking contrast to it. 30 The smooth wide annular top part D and the slender upward projection E, with its cylindrical sides and flat top, are distinctive and make a marked contrast to the rough band C.

What I claim is—

35 The design for tire-valve caps, substantially as shown and described.

In witness whereof I have hereunto signed my name in the presence of two subscribing witnesses.

GEORGE H. F. SCHRADER.

Witnesses:

GEORGE H. FRASER,
THOMAS F. WALLACE.
